CLAIM

The ornamental design for a key module as shown and described.

DESCRIPTION

FIG. 1 is a perspective view of a key module showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the key module in the usage status; and,

FIG. 10 is another perspective view thereof showing the key module in the usage status.

The broken lines shown in the figures are for the purpose of illustrating portions of the key module and form no part of the claimed design. The even-dashed broken lines in FIG. 9 and FIG. 10 are for the purpose of depicting environment and form no part of the claimed design.

1 Claim, 10 Drawing Sheets
